UNITED STATES PATENT OFFICE.

BENJAMIN TURTON, OF NEWARK, NEW JERSEY, ASSIGNOR OF THREE-FOURTHS TO JOSEPH L. DOREMUS, JOHN TURTON, AND HARRY TURTON, ALL OF SAME PLACE.

SPRING-MOTOR.

SPECIFICATION forming part of Letters Patent No. 402,548, dated April 30, 1889.

Application filed March 23, 1888. Serial No. 268,217. (Model.)

To all whom it may concern:

Be it known that I, BENJAMIN TURTON, a citizen of the United States, residing at Newark, in the county of Essex and State of New Jersey, have invented certain new and useful Improvements in Spring-Motors; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to obtain increased power by a combination of a series of springs with suitable mechanisms at a reduced cost of construction, and is an improvement upon the mechanism heretofore described in an application for Letters Patent made by me and filed August 17, 1887.

The invention consists in the arrangements and combinations of parts, substantially as will be hereinafter set forth, and finally embodied in the clauses of the claim.

Referring to the accompanying drawings, in which like letters of reference indicate corresponding parts in each of the several figures, Figure 1 is a side elevation of a portion of the improved motor, the balance-wheel, with its gear-connections, being removed. Fig. 1^a is a side elevation of the improved motor complete. Fig. 2 is a side elevation of a portion of the balance-wheel with its gear-connections. Fig. 3 is an elevation of one pair of the motor-springs. Fig. 4 is an end view of Fig. 3. Fig. 5 is an elevation of an auxiliary wheel with its gear-connection. Fig. 6 is a top plan view of the motor frame and gearing, the springs being omitted.

In said drawings, D indicates the frame or bed of a machine.

B is the main or driving shaft, having pinion *t*, into which meshes gear-wheel *h*². *h*, *h'*, *h*², *h*³, *h*⁴, and *h*⁵ are a series of gear-wheels on spring-carrying shafts *n*, and each meshing into the one adjoining. Thus *h* meshes into *h'*, *h'* into *h*², *h*² into *h*³, and *h*³ into *h*⁴, and *h*⁴ into *h*⁵, and *h*⁵ into *h*². By this arrangement the power of the gear-wheels *h* *h'* *h*² *h*³ *h*⁴ *h*⁵ is all trans-

mitted to and concentrated in gear-wheel *h*², which alone transmits the concentrated power to the main driving-shaft, the power of *h* being transmitted to *h'*, which transfers it, together with its own power, to *h*², while *h*⁵ transfers its power to *h*⁴, which transfers it, together with its own power, to *h*³, which, in its turn, transfers this concentrated power of *h*⁴ and *h*⁵, which it has received, as well as its own power, to *h*².

a is a gear-wheel on the rear of a driving-shaft, B, and meshing into pinion *b* on shaft *c*, on which shaft is gear-wheel *d*, which meshes into pinion *e* on fly-wheel shaft *f*. On the outside of the frame and on driving-shaft B is a gear-wheel, *g*. (Shown in Fig. 2.) This gear-wheel meshes into a pinion, *i*, on balance-wheel shaft *k*, carrying balance-wheel *m*. This balance-wheel shaft is supported at its outer end in proper journal-bearings in frame *n'*.

On the rear of the frame D is an auxiliary frame, *o*, Fig. 5, in which is journaled a shaft, *p*, carrying gear-wheel *q*, imparting its motion and power to pinion *r* on the rear of driving-shaft B.

On shaft *f* is a fly-wheel, *s*, and against its outer periphery is brought to bear the brake *u*. This brake consists of a metallic shoe or brake, *u*, adapted to bear upon the surface of the fly-wheel *s*, and is supported by a lever, *v*, having its opposite end forked so as to partially enfold the hollow rod 1, which carries the governor 2. This lever *v* is pivoted to an arched support, *w*, secured to frame D, as seen in Fig. 1. Opposite to the brake *u* and arranged to bear upon the opposite side of the fly-wheel *s* is a shoe, *z*, Fig. 1. This shoe is attached to a thumb-screw, *4*, working in a threaded socket in cross-bar 5, secured to the frame D.

On each of the spring-shafts *n* are secured double springs 6, separated by a loose partition, 7, one end of each of said springs being secured to the frame D, as seen at 8, Figs. 1, 3, and 4. These springs when wound up are prevented from unwinding by the common and well-known means of the pawl and ratchet-wheel.

In my improved motor, the gear-wheels being loose on their respective spring-carrying shafts, the same do not turn when the springs are wound up, and thus I am enabled to wind up any of the springs without stopping the machine or in any way interfering with the running of the machine. This is accomplished by securing the ratchet to the spring-carrying shaft and attaching the pawl with its holding-spring to the gear-wheel, as shown in Fig. 4. This allows the gear-wheel to turn with the spring-bearing shaft when it is unwinding or transmitting power, but not to revolve with the shaft when the springs are wound up. The springs are wound up in the usual manner by a crank placed on the end of the shaft. By this arrangement of a loose gear-wheel I am enabled to wind up any of the springs without in any manner interfering with the working of the others.

It is manifest that the frame can be extended and any number of spring-bearing shafts could be employed, thereby greatly increasing the power of the machine.

On the shaft *p* is placed gear-wheel *q*, as seen in Fig. 5, and is loose on the shaft. This shaft also carries and has secured to it one end of a spring, *9*, the other end of the spring being secured to a lug, *10*, on frame *o*. This gear-wheel works in the same manner on its shaft as gear-wheels *h*, &c., already described. The said gear-wheel *q* meshes with a pinion, *r*, on the rear of the main shaft, and its revolution aids and assists the various motive springs while unwinding or while one of the series is being wound up while the machine is in motion. When winding up the machine the shoe *3* is screwed up against the fly-wheel, so as to prevent any of the wheels from revolving when one or more of the series of motive springs may be wound up according to the amount of power required.

To start the machine, the shoe *3* is gradually released from contact with the fly-wheel by means of the thumb-screw, the action of the spring (or springs) that are wound up

causes all the wheels to revolve, and the degree of speed is regulated by the regulator, the brake being caused to impinge upon the fly-wheel to a greater or less degree, according as the lever *v* is raised or lowered by the regulator, as will be understood. The frame *D* can be secured to feet, if desired.

Having thus described the invention, what I claim as new, and desire to secure by Letters Patent, is—

1. In a spring-motor, the combination, with the main frame and driving shaft of the machine, of a supplemental frame, *o*, shaft *p*, journaled in said frame *o*, spring *9*, auxiliary gear-wheel *q*, independent of but connected with the spring driving mechanism, and pinion *r*, connecting said auxiliary gear-wheel with the driving-shaft of the machine, substantially as shown, and for the purposes set forth.

2. In a spring-motor, an auxiliary spring driving mechanism consisting of a supplemental frame, *o*, shaft *p*, journaled in said frame *o*, spring *9*, auxiliary gear-wheel *q*, independent of but connected with the spring driving mechanism, and pinion *r*, connecting said auxiliary gear-wheel *q* with the main driving-shaft of the machine, in combination with the main spring driving mechanism consisting of a series of spring-bearing shafts, *n*, gear-wheel *h*, revolving on one of said shafts *n* and meshing into pinion *t* on main shaft, a series of gear-wheels revolving on similar shafts, *n*, and arranged to transmit their united power to gear-wheel *h*, and pawl-and-ratchet devices connecting said gear-wheels with their respective shafts, all as shown and described, and for the purposes set forth.

In testimony that I claim the foregoing I have hereunto set my hand this 3d day of March, 1888.

BENJAMIN TURTON.
